UNITED STATES PATENT OFFICE.

HERBERT A. FABER, OF CINCINNATI, OHIO, ASSIGNOR TO THE FORMICA INSULATION COMPANY, OF CINCINNATI, OHIO, A CORPORATION OF OHIO.

TUBE-FORMING MACHINE.

Application filed February 7, 1921. Serial No. 443,137.

To all whom it may concern:

Be it known that I, HERBERT A. FABER, a citizen of the United States, residing at 4614 Spring Grove Avenue, Cincinnati, in the county of Hamilton and State of Ohio, have invented a new and useful Improvement in Tube-Forming Machines, of which the following is a specification.

This invention relates particularly to a machine for forming tubing, a fabric, such as paper, which has a varnish or adhesive applied to the surface thereof.

The primary object is to provide an improved machine of simple construction, which can be easily operated, and which is capable of producing a highly desirable product of great uniformity.

The invention is illustrated in its preferred embodiment in the accompanying drawings, such embodiment being particularly adapted to form tubing for insulation purposes, or for other purposes, from the fabric, such as paper, coated or impregnated with a phenolic condensation product varnish. The paper is dried after the varnish is applied, and in this condition the paper is passed through the machine illustrated and is wound upon a mandrel, the condensation product being fused by means of heat applied through one of the pressure-rolls. In this manner, the plies of paper formed by winding the paper on the mandrel are thoroughly bonded together. While the binder employed is a phenolic condensation product, it is capable of being converted into a hard infusible and insoluble product by means of heat. Some of the heat is applied in the tube forming operation, but this is not sufficient to thoroughly convert the binder to the final infusible and insoluble state. Such conversion may be effected by baking the tubes in an oven at a temperature in the neighborhood of 100° C., or higher; or the tubes, after being formed on a mandrel, may be subjected to pressure between dies and a heated press, if desired, and the conversion of the binder to the insoluble state may be effected in the dies.

In the drawings—

Fig. 1 represents a perspective view of the improved machine, the lower portion of the frame being broken away; Fig. 2, an enlarged broken plan view showing the mandrel and the pressure-rolls and portions of the slides or carriages which carry the

pressure-rolls; Fig. 3, a broken longitudinal vertical section, taken as indicated at line 3 of Fig. 2; and Fig. 4, a broken transverse vertical section, taken as indicated at line 4 of Fig. 3.

In the construction illustrated, referring to Fig. 1, A represents the frame of the machine, said frame being provided with a top, or bed, A'; B, a mandrel which is removably supported in standards or bearings B', B², which are mounted on the top of the frame; C, a carriage or slide mounted in guides on the top of the frame and carrying a heated pressure-roll C' disposed at one side of the mandrel; D, a carriage or slide mounted in guides on the top of the frame and carrying pressure-rolls D' and D² located on the other side of the mandrel, that is opposed to the heated roll C', the axis of the roll D' being above the axis of the mandrel, and the axis of the roll D² being below the axis of the mandrel, while the axis of the roll C' is in the same plane as the axis of the mandrel; C², mechanism for shifting the carriage C and applying pressure through the roll C' to the tube being wound on the mandrel; D³, mechanism for shifting the carriage D and applying pressure through the medium of the rolls D' and D²; C³ and D⁴, eccentric devices for shifting the position of the rock-shafts of the mechanisms C² and D³, in order that the pressure rolls may occupy the necessary position in the tube forming operation, regardless of the size of the mandrel, or of the tube being formed; E, a roll of paper carried by a drum E'; F and F', guide rollers about which the paper passes from the roll E; and F², an adjustable roll disposed near the mandrel and from which the paper passes directly to the mandrel.

The frame A may be of any suitable construction. In the form shown, it comprises a suitable standard on which the top A' is rigidly secured by any suitable means.

The mandrel B is equipped at one end with a handle or a crank B', by means of which the mandrel may be rotated to wind the coated or impregnated paper thereon. The mandrel is made readily removable from its supporting standards B' and B² in any suitable manner. Thus, in Figs. 2 and 4, the standard B² is shown as provided with a stub-shaft 1, which is adjustable through the standard and may be secured in

adjusted position by any suitable means, as by means of the clamping device 2. The stub-shaft is equipped with a hollow cone 3, which receives the end of the mandrel-shaft.

- 5 When desired, the stub-shaft 1 may be shifted longitudinally in the bearing to enable the mandrel to be taken out.

The heated roll C' is suitably journaled in the carriage C. Any suitable means may 10 be provided for heating the pressure-roll C'. For example, the pressure-roll may be provided with a projecting hollow shaft 4, with which may be connected a hose 5, through which steam may be admitted to the roll.

- 15 The carriage shifting mechanism C² preferably comprises a rock-shaft 6, equipped with an actuating handle 7; short arms 8 rigidly secured to the rock-shaft; links 9, having their inner ends pivotally connected 20 with the carriage and having their outer ends extending freely through bearing blocks 10, which are equipped with trunnions or pivots 10^a, which are journaled in the free end of the arm 8; and heavy coil 25 springs 11 encircling the links 9 and interposed between shoulders at the inner end of said links and the bearing blocks 10, which are freely slideable on the outer ends of said links. The outer ends of the links 9 are 30 equipped with collars 12, which are adapted to engage the blocks 10, so that the links will serve in retracting the carriage.

The mechanism D³ for shifting the carriage D is of the same construction, and the 35 parts are similarly designated.

- The eccentric devices C² and D³ are alike in construction and operation. The rock-shafts 6 are, in both cases, shiftable longitudinally of the frame in elongated slots 13, 40 with which the frame is provided. These eccentric devices comprise an eccentric shaft 14, journaled in the frame and equipped with a pair of eccentrics 15 and a pair of eccentric rods 16, connecting the eccentrics 45 with the rock-shaft 6. The eccentric shaft is equipped with an actuating handle 17. It will be understood that when the eccentric shaft is turned in its bearings, the rock-shaft 6 will be adjusted or shifted in its bearings, 50 thus giving a new fulcrum point for the carriage shifting mechanism to work from. Thus, there are provided simple, positive and easily operated devices for adjusting the positions of the rock-shafts 6, and in this 55 manner adjusting the pressure-rolls to accommodate mandrels of varying sizes or tubes of varying sizes.

The mechanisms C² and D³ for shifting the pressure-rolls into and out of the operative position constitute lever-and-link devices, which enable the carriages to be shifted quickly; and these devices have associated with them springs for transmitting the pressure to the pressure-rolls, so that the pressure-rolls can yield as much as may be

necessary, as the thickness of the tube increases in the tube forming operation.

The carriages C and D are shown connected with the frame by means of longitudinal guides 18, as will be understood from 70 Figs. 1 and 4.

The pressure-roll carriages are shown in Fig. 3 in the position which they occupy when the pressure-rolls are in position to compact the plies of paper together as the 75 paper is wound upon the mandrel. It will be noted that the arms 8 and links 9 constitute, in effect, a toggle joint device or toggle lever device. That is, when these members are in the full line position shown in 80 Fig. 3, they are in substantial alignment, so that very great force can be exerted through the springs 11. The arms 8 may be carried slightly past the dead center and brought into engagement with stubs 19, so that the 85 toggle lever arrangement will be locked in position, if desired. The dotted lines in Fig. 3 show the manner in which the links 9 may be retracted to withdraw the carriage.

The paper carrying drum E' is shown 90 provided with a friction device 20, which may be of any desired construction.

In the operation of the machine, the coated or impregnated paper passes from the paper roll E beneath the guide roll F, 95 thence about the guide roll F', and thence over the guide roll F'', from which it passes between the mandrel and the pressure-roll C', and is wound upon the mandrel. The course of the paper is indicated by the 100 dotted line 21 in Fig. 1. Assuming the paper to be coated or impregnated with a fusible binder, such as a dried varnish composed of a phenolic condensation product, shellac or the like, the paper may be wound upon the mandrel by turning the mandrel through the medium of the crank B'; and assuming the pressure-roll to be in the position indicated in Fig. 3, the heated pressure-roll will cause the binder to be fused, 105 and the plies of paper will be closely compacted together by the pressure-rolls as the winding proceeds. After a suitable thickness of tube has been produced, the paper is cut, the mandrel is given a few more turns, and the tube and mandrel may then be removed from the machine to enable a 110 fresh mandrel to be inserted.

Depending upon the nature of the binder used and the character of the product being produced the tube may be treated further after removal from the tube forming machine, or it may become a finished product in the tube forming machine. If a phenolic condensation product is employed as a 115 binder, further treatment is desirable, either in a heated press, or in an oven or the like, which will serve to convert the condensation product to the final insoluble condition. If shellac be employed as a binder, the tube 120

may be finished in the tube forming machine; or if great accuracy is desired, the tube may be further pressed in a hot press.

The improved machine enables a very uniform and highly desirable product to be produced quickly, cheaply and without entailing unduly heavy work upon the operator. Moreover, the carriage shifting mechanisms may be readily adjusted to enable the machine to be used in producing tubes of varying sizes.

Figs. 2 and 3 show a slight modification in that the rock-shaft 6 is journalled in an adjustable slide or carriage 22, connected with the guides 18; and in this modification, the rear ends of the eccentric rods 16 are connected with the carriage or shiftable fulcrum-carrier 22 by pivots 23. Also, the rock-shaft 6 is, in the modification, journalled in the shiftable support 22.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is

1. In a machine of the character set forth, the combination of a mandrel, carriages mounted on opposite sides thereof, pressure-rolls mounted on said carriages, carriage shifting mechanisms, and means for adjusting the fulcrums from which said carriage shifting mechanisms operate.

2. In a machine of the character set forth, the combination of a mandrel, carriages mounted on opposite sides thereof, pressure-rolls mounted on said carriages, rock-shafts shiftably mounted on the frame, means for shifting said rock-shafts and operative connections between said rock-shafts and said carriages.

3. In a machine of the character set forth, the combination of a mandrel, carriages mounted on opposite sides thereof, pressure-

rolls mounted on said carriages, rock-shafts shiftably mounted on the frame, and operative connections between said rock-shafts and said carriages, comprising arms mounted on the rock-shafts, links extending between said arms and said carriages, and springs interposed between said arms and said carriages.

4. In a machine of the character set forth, the combination of a mandrel, carriages disposed on opposite sides of said mandrel, rock-shafts mounted on the frame, eccentric devices for shifting said rock-shafts, operative connections between said rock-shafts and said carriages, and pressure-rolls mounted on said carriages.

5. In a machine of the character set forth, the combination of a mandrel, carriages mounted on opposite sides thereof, pressure-rolls journalled in said carriages; rock-shafts shiftably mounted on the frame and operatively connected with said carriages, and eccentric devices mounted on the frame and connected with and serving to shift said rock-shafts.

6. In a machine of the character set forth, the combination of a frame provided at its upper portion with longitudinal guides, a mandrel having its ends journalled on said frame, a carriage mounted to move in said guides, a pressure roll mounted on said carriage and adapted to co-act with said mandrel, a suitably mounted rock-shaft equipped with an operating lever and equipped with arms, links pivotally connected with said carriage, slidable connections between said links and the extremities of said arms, and springs interposed between the carriage and said slidable connections, said links and arms affording toggle joints which may be thrown into locking position, the springs permitting recession of the carriage as the thickness of the tube being formed on the mandrel increases.

HERBERT A. FABER.
